UNITED STATES PATENT OFFICE.

DONALD K. MOORE, OF DETROIT, MICHIGAN.

DESIGN FOR A FINGER-RING.

51,929.

Specification for Design.

Patented Apr. 2, 1918.

Application filed January 29, 1918. Serial No. 214,423. Term of patent 14 years.

To all whom it may concern:

Be it known that I, DONALD K. MOORE, a citizen of the United States, residing at Detroit, in the county of Wayne and State of Michigan, have invented a new, original, and ornamental Design for Finger-Rings, of which the following is a specification, reference being had to the accompanying drawing, forming part thereof.

In the drawing, Figure 1 is a front view of a ring embodying my new design. Fig. 2 is a side view thereof.

I claim:

The ornamental design for a finger ring, as shown.

DONALD K. MOORE.
